INVENTOR:

august rickert,
BY Fred C. Graetz, ATT'Y.

UNITED STATES PATENT OFFICE.

AUGUST RICKERT, OF NEWARK, NEW JERSEY.

DESIGN FOR A WATCH-CHAIN.

SPECIFICATION forming part of Design No. 21,426, dated March 22, 1892.

Application filed February 3, 1892. Serial No. 420,237. Term of patent 7 years.

To all whom it may concern:

Be it known that I, AUGUST RICKERT, a citizen of the United States, residing at Newark, in the county of Essex and State of New Jersey, have invented and produced a new and original Design for a Watch-Chain or other Similar Articles, of which the following is a specification, reference being had to the accompanying drawing, forming a part thereof.

10 In the drawing the figure is a perspective view of my design for a watch-chain or other similar article. This view is deemed sufficient to fully illustrate my design, the leading feature of which consists in the peculiar configuration or form of the several links intertwined to form the watch-chain or other similar article, as will be hereinafter fully set forth and claimed.

15 Referring to the accompanying figure in the

20 drawing, *a* indicates the several links formed into a series of curves and terminating in the free ends *a'*, and these links intersect and cross one another, terminating in a series of curves or convolutions of a spiral form having the free projecting ends and the several 25 structures being intertwined one with another, as will be seen and understood upon reference to the drawing.

What I claim is—

25 The design for a watch-chain or similar article, herein shown and described.

In testimony that I claim the invention set forth above I have hereunto set my hand this 15th day of January, 1892.

AUGUST RICKERT.
